ACTUATING MECHANISM FOR PRESSING MACHINES

Original Filed Oct. 29, 1928

UNITED STATES PATENT OFFICE

ERNEST DAVIS, OF SYRACUSE, NEW YORK, ASSIGNOR TO THE PROSPERITY COMPANY INC., OF SYRACUSE, NEW YORK, A CORPORATION OF NEW YORK

ACTUATING MECHANISM FOR PRESSING MACHINES

Application filed October 29, 1928, Serial No. 315,704. Renewed October 29, 1930.

This invention relates to pressing machines or more particularly actuating mechanism for machines having an opening and closing movement as garment and laundry pressing machines, and it has for its object a particularly simple mechanism for varying the leverage or ratio between the prime mover and the element or press head to which the motion is transferred so as to convert a comparatively great movement of the prime mover into a small powerful movement of the press head when the latter is moving into final pressing position.

An object of this invention is to improve the operation of toggle actuated pressing machines by providing boosting mechanism for compensating for the changes in the length of the toggle when the same is near straightened position. A more specific object of the invention is to improve upon the compensating mechanism shown in my Patent 1,682,373, issued August 28, 1928. The compensating mechanism shown in the patent referred to possesses the disadvantage that if an eccentric is used and turned by a straight radial arm the variation in the length of the toggle, as the same approaches and passes straightened position, is not at the most desirable rate to fully compensate for the change in the straight line distance between the ends of the toggle.

The invention consists in the novel features and in the combinations and constructions hereinafter set forth and claimed.

In describing this invention, reference is had to the accompanying drawings in which like characters designate corresponding parts in all the views.

Figure 1 is a side elevation of a pressing machine embodying my invention.

Figure 2 is a diagrammatic view illustrating the operation thereof.

Figure 3 is a diagrammatic view illustrating the operation of a machine in which the leverage is not modified or the operation of a machine on which this invention is an improvement.

This pressing machine comprises generally, cooperating pressing elements, one of which is movable toward and from the other, mecha-

nism for actuating the movable element comprising a prime mover as the movable member of a motor, motion transmitting connections between the movable motor member and the movable pressing element comprising means automatically operated by the movement of said connections to vary the leverage or the ratio of the leverage between the prime mover or the movable member of the motor and the movable pressing element, particularly so as to transfer a comparatively large movement of the prime mover compared to the movement of the press head into a small powerful movement of the press.

The cooperating pressing elements include a stationary buck 1 mounted on a suitable frame 2 and a head 3 movable toward and from the buck 1, this head being carried by a lever 4 pivoted between its ends at 5 to the frame. The actuating mechanism comprises a suitable motor as a cylinder 6 having a piston movable therein and motion transmitting connections between the piston rod 7 and the head 3.

The motion transmitting connections in addition to the lever 4, comprise a toggle, here shown as including links 8 and 9 pivoted respectively at 10 to the base of the frame and at 11 to the rear arm of the yoke lever 4, and the motion of the piston rod 7 is transferred to the toggle through a lever 12 constituting a forward extension from the toggle link 8 and together with said link forming a bell crank lever. The piston is single acting.

The press head is opened by countersprings 13, 14. There is an additional spring 15 which acts to check the final closing of the head.

The construction thus far described, in itself, forms no part of this invention.

The means for varying the ratio of movement between the prime mover or piston rod 7 and the head 3 is associated with the toggle links and acts as the toggle links are moving into their extended position or final position from folded position, and comprises means for automatically shortening the effective length of the toggle as the press head 3 comes down on the work on the buck, and thereafter automatically extending the toggle. Specifi-

5 cally the means comprises a pivot pin 16 rotatably mounted in a bearing in link 8 and having an eccentric portion 17 rotatably mounted in a bearing 18 at the lower end of the link 9, and means for rotating the eccentric at a predetermined point in the movement of the toggle. The pin 16 is here shown as formed with a rock arm 19 projecting forwardly at an angle to the toggle when it is in straightened position and coacting with a 10 fixed cam 20 provided on the frame.

15 The eccentric is normally arranged with its major radius in line with the link 8 when the toggle is folded or in the position A indicated by the dot and dash lines, Figure 2, and remains in this position in order to effect a quick closing of the press from wide open position toward closed position or while the toggle is traveling from position A to a preliminary closed position B, and the piston rod 20 is traveling from position A to position B and the press head traveling from position A to position B which is nearly closed position. When in position B, the head is said to be 25 preliminarily closed or is in a closed position by which little or no pressure is applied as distinguished from final position when final heavy or full pressure is applied.

30 The arm 19 then engages and begins to ride up a high portion 21 of the cam thus turning the eccentric downwardly in an anti-clockwise direction or backing it off and shortening the effective length of the toggle while the parts are moving from position B 35 to position C. This shortening of the toggle effects a short powerful movement of the head from position B to position C while the toggle is moving a comparatively long distance from position B toward full line position 40 C and while the lever 12 and hence the piston is traveling from position B to position C in a longer arc compared with the movement of the head between the points B, C.

45 As the toggle reaches substantially straightened position the free end of the arm 19 follows a retreating or backed off portion 23 of the cam. This portion of the cam is of slot formation, the side 24 forming the 50 other side of the slot. When the free end of the arm 19 moves along between the cam faces 23, 24 the arm will be moved in a clockwise direction to rotate the eccentric so as to increase the length of the toggle. The form 55 of the cam faces 23, 24 is made such that the length of the toggle will be increased fast enough to compensate for the fact that as the toggle moves beyond straightened position the ends of the toggle tend to move closer together. Any movement of the ends of the toggle toward one another when the 60 press is closed will obviously reduce the pressure applied between the pressing elements.

65 During the movement of the toggle beyond

straightened position the lower side 24 of the cam forces the arm upwardly.

Ordinarily in a machine of this type having a toggle as seen in Figure 3, the wide open position of which is indicated by the 70 dot and dash line W and the position of the parts in the preliminarily closed position of which is illustrated by the line X, the arcs of movement are the same as those indicated by the lines A and B, Figure 2. However, 75 during continued movement, from the position indicated by the lines X to the position indicated by the line Y, the toggle travels a shorter distance than it does from the position indicated by the line B to the position 80 indicated by the line C, Figure 2, but the head travels the same distance as in Figure 2.

85 This traveling of the head with greater movement of the toggle, in my invention as seen in Figure 2, is brought about by the eccentric moving anti-clockwise from its normal position where its major radius is in line with the link 9 out of such position.

90 As shown in Figure 3, during the final closing of the press head, the head moves from position Y into full line position Z, while the toggle moves from position Y to the full line position Z. In this final position Z the toggle may form a straight line but it is important that the press be adjusted so that the toggle will not move beyond straight line position in applying final pressure. If the toggle moves beyond straight line position the ends will tend to come together and the head will rise slightly and lessen the pressure of the machine. With the pressing machine embodying my invention, illustrated in Figure 2, the toggle may move from position C to the full line position 95 D in moving the pressing head from position C to position D. This movement may take the toggle beyond straightened position but the compensating means furnished by the cam operated eccentric will lengthen the toggle 100 sufficiently to compensate, or more than compensate if desired, for the change in angle between the toggle links which tends to bring the ends of the toggle closer together. Obviously the ends of the toggle are at their greatest distance from one another when the toggle is in straight position. To obtain maximum pressure and operating efficiency the pressing machine illustrated in Figure 3 must be adjusted so that when maximum pressure 105 is applied the toggle will occupy position Z. With the pressing machine illustrated in Figure 2 maximum operating efficiency at substantially maximum pressure may be obtained with the toggle occupying a wide 110 range of positions between position C and D. In view of the changes in the thickness of the padding and the work on which the press is used the advantage of the machine 115 shown in Figure 2 is at once obvious.

The flow of motive fluid to and from the cylinder is controlled by any suitable means and includes a manual or push button 25 and a release lever 26. The control mechanism forms no part of this invention. It is merely necessary to bear in mind that the operation of the push button 25 permits the motive fluid as air to enter the cylinder and actuate the piston therein and the air in the cylinder holds the press closed; and that to open the press, the release lever 26 is operated to exhaust the air from the cylinder so that the press will open under the action of the countersprings 13 and 14.

What I claim is:

1. A pressing machine including cooperating pressing elements, one of which is movable toward and from the other, mechanism for actuating the movable element including an actuator, motion transmitting means between the actuator and the movable pressing element including a toggle, means for automatically shortening the effective length of the toggle as the movable press element moves from preliminary closed position into final closed position, and means for thereafter increasing the length of the toggle as the toggle passes its dead center line.

2. A pressing machine including cooperating pressing elements, one of which is movable toward and from the other, mechanism for actuating the movable element comprising a motor including a movable member, and motion transmitting connections between the movable motor member and the movable pressing element including a toggle, the joint connecting the toggle links comprising a pin journalled in one of the links of the toggle and having an eccentric journalled in the other link of the toggle, the eccentric being normally arranged with its greatest radius in line with one of the links of the toggle when the toggle is folded, the eccentric having a rock arm, a stationary cam arranged in the path of the rock arm to rock the same and shift the eccentric as the toggle moves toward its final extended position, said cam having means to move the rock arm first in one direction and said cam also having means to move the arm in the reverse direction to shorten the effective length of the toggle and finally lengthen the toggle.

3. A pressing machine including cooperating pressing elements, one of which is movable toward and from the other, mechanism for actuating the movable element including a prime mover and motion transmitting connections between the prime mover and the movable element including a toggle, one of the joints of the toggle having a bearing and an eccentric rotatably mounted in the bearing, the eccentric having a rock arm, a cam for coacting with the rock arm, the cam and the rock arm being normally spaced apart when the toggle is folded and one being movable

into engagement with the other as the toggle straightens, said cam having means to first rock the rock arm and the eccentric in one direction to shorten the effective length of the toggle as the toggle approaches straightened position and said cam also having means to move the rock arm in the opposite direction to cause the eccentric to increase the effective length of the toggle.

4. In a garment pressing machine in combination a frame; cooperative pressing elements and actuating means therefor including a toggle mechanism having means for automatically varying the length of the toggle as said toggle straightens; said means including a pin and an eccentric forming one of the pivotal connections of the toggle; cam means and cam follower means, one of which is mounted on the frame and the other of which is operatively connected with the eccentric, for automatically rotating the eccentric relatively to the toggle links as the toggle straightens.

5. In a garment pressing machine in combination a frame; cooperative pressing elements and actuating means therefor including a toggle mechanism having means for automatically varying the length of the toggle as said toggle straightens; said means including a pin and an eccentric forming one of the pivotal connections of the toggle; an arm connected with the eccentric; cam means mounted on the frame and arranged in the path of the arm to actuate it to rotate the eccentric as the toggle approaches a straight line and as the toggle moves beyond straight line position.

6. In a garment pressing machine in combination a frame; cooperative pressing elements and actuating mechanism therefor including a toggle mechanism having links; pivot means for the links including a shaft on which one of the links is mounted and eccentric means on the shaft for engaging the other link; a bearing on said other link for engaging the eccentric; an arm connected with the eccentric means and extending radially therefrom; and cam means mounted on the frame in position to engage said arm as the toggle straightens.

In testimony whereof, I have hereunto signed my name, at Syracuse, in the county of Onondaga, and in the State of New York, this 25th day of October, 1928.
